UNITED STATES PATENT OFFICE.

ABNER DOBLE, OF DETROIT, MICHIGAN, ASSIGNOR, BY MESNE ASSIGNMENTS, TO DOBLE-DETROIT STEAM MOTORS CO., OF DETROIT, MICHIGAN, A CORPORATION OF DELAWARE.

APPARATUS FOR BURNING FUEL.

1,340,383.

Specification of Letters Patent. Patented May 18, 1920.

Application filed September 23, 1916. Serial No. 121,801.

To all whom it may concern:

Be it known that I, ABNER DOBLE, a citizen of the United States of America, and resident of Detroit, Wayne county, Michigan, have invented a certain new and useful Improvement in Apparatus for Burning Fuel, of which the following is a specification.

My invention relates to that class of steam generating plants more particularly designed for use in the propulsion of vehicles such as automobiles, motor boats, motor cars and the like, and my object is to provide a generating plant of this type or class which will economically and efficiently operate to generate or produce steam promptly in accordance with the varying demands therefor, which will accomplish the initial or starting generation of steam in the least period of time, and which in general overcomes or eliminates the objections in the various steam generating plants of this class which have heretofore been proposed, or are in use at the present time, my purpose being further to provide an improved apparatus of burning fuel economically and effectively, avoid back firing in the burners and confine or concentrate the heat in a manner to be most efficiently utilized for the generation of the steam. Other objects of my invention will appear hereinafter.

The drawings illustrate a structure and arrangement of parts which embody my invention and which effectively carry out my improved method of burning fuel.

In the drawing—

Figure 1 is a diagrammatic view illustrating the various parts as adapted more particularly for the propulsion of an automobile and thereby illustrating their association and relative position in a vehicle of this class.

Fig. 2 is an enlarged vertical section of the steam boiler and the burner and their associated parts.

Fig. 3 is a vertical section through the boiler and burner, but taken at right angles to that shown in Fig. 2, and

Fig. 4 is an enlarged detail section substantially on the line 4—4 of Fig. 2.

In the drawings, I have illustrated a portable steam generating plant designed more particularly for use in automobiles and

like vehicles, but, of course, it will be obvious to one skilled in the art, after having obtained an understanding of my invention from the disclosures herein made, that the principles and functions which characterize my invention may be embodied in and applied in other ways and in modified structures without departing from the scope and spirit of my invention, and I desire it to be so understood.

The diagram in Fig. 1 is intended to illustrate the arrangement and association of the structural parts of a steam generating plant for automobiles or motor-propelled vehicles. In this system, and for this purpose, I use a steam condenser for the purpose of conserving the water supply, but where water is plentiful and the conservation thereof is a secondary consideration, as for instance in the case of motor boats and even stationary plants, the condensing system may, if desired, be dispensed with. The condenser, which I have illustrated merely diagrammatically as A, may be of any suitable type which will meet the particular requirements, but I prefer to use a condenser constructed in the manner of the so-called honey-comb radiator or water cooler commonly used in motor-propelled vehicles of the internal combustion engine type. This condenser is preferably positioned at the front end of the vehicle because in the explosion engine type of vehicle custom has placed it there. It has, as is well known, innumerable small intercommunicating passages A' through which the water circulates, but through which in this case the exhaust steam from the engine circulates, this exhaust steam being conducted to the top of the condenser by the pipe A². Innumerable openings A² are provided around the steam passages for the cold outside air to pass and effect a condensing operation. I have described the condenser somewhat in detail because, as will hereinafter appear, I utilize some of the dissipated heat from the condenser to warm or heat the air for the combustion mixture in the burner. The feed water pipe 1 leads from the lower end of the condenser to the reserve water tank 1².

The boiler B is preferably positioned just in the rear of the condenser and mounted on the frame, which is represented by the two

channel beams 3, in any suitable manner. The boiler which I have shown is of rectangular form for the sake of compactness in construction, and to better utilize the restricted space on the frame of an automobile. It involves a shell or heat retaining chamber B¹, the walls 4 of which are constructed of suitable insulating and refractory lining. This chamber, however, is divided into two compartments by a heat wall or partition B² which terminates short of the top to provide communication between the two compartments. Each compartment contains a group of vertically or substantially vertically-disposed water tubes 10. These tubes are in transverse parallel rows, but all of the tubes are spaced apart preferably a distance substantially equal to the diameter of the tubes so as to provide space around the tubes for the passage of heat and products of combustion. Each row of tubes has a common header 11 at its upper end, and a similar common header 12 at its lower end to which the ends of the tubes are fastened. The upper headers are of larger diameter than the tubes, so that they will be in actual contact with each other and form in effect an upper wall for each compartment and at the same time be directly subject to the heat. The lower headers are, however, of such diameter that spaces are provided therebetween for the passage of the heat and products of combustion. The group of tubes which are contained in the compartment C constitutes the evaporator and super-heater portions of the boiler, while that group within the compartment D constitutes the economizer or feed water heater portion of the boiler; hence these two groups are independent in that sense. All of the upper headers of the evaporator and super-heater group are connected to a common steam manifold 13 which collects the steam therefrom and which is connected by a pipe 14 to the source of steam consumption, which in a plant for automobiles, is the engine (not shown), although, of course, a suitable control throttle should be interposed in this steam line. In like manner, the lower headers of this same group are connected to a common water manifold 14', which distributes the water to the several lower headers, whereby the water will rise to the proper level uniformly in all of the evaporator tubes. Any suitable regulator for controlling this water level may be used. In like manner all of the upper headers of the tubes in the group D connect with a common manifold 15 and all of the lower headers to a common manifold 16, which latter manifold receives water from the feed water line 1 and distributes it to the economizer tubes equally. A suitable force pump 1^b is provided in the water line 1 to inject the water into the

boiler against the boiler pressure. The upper manifold 15 of the economizer section delivers heated or warmed water to the lower water manifold 14 of the evaporator section by means of suitable pipe connections 15^a. The burner, which is positioned below the evaporator section or group of tubes, supplies heat to the compartment C, converting the water in the lower portion of the tubes into steam which rises to the upper portion of said tubes and into the headers where it is subjected to the continued action of the heat, this process resulting in the drying and superheating of said steam. The heated products of combustion pass over the partition wall and downwardly through the compartment D where the economizer tubes are located. The water in these latter tubes thus becomes heated and rises through the upper headers 85 and manifold 15, and from thence passes into the water manifold of the evaporator section of the boiler.

The exhaust products of combustion, after passing down through the compartment D, 90 where they may, if desired, be discharged into the open air through the flue 17, or if desired may be utilized in any other suitable manner. The boiler itself constitutes the subject-matter of my co-pending application Serial No. 121,802 filed September 23, 1916. It can, however, be regarded for certain purposes of this application as representative of any suitable boiler construction in relation to my improved apparatus for 100 burning fuel. I have, however, described the boiler somewhat in detail to show the peculiar and special adaptability of this particular boiler with respect to the burner and other parts of my improved system. 105

As before mentioned, I position the fuel burner beneath the evaporator and super-heater section of the boiler in such manner that the heat may be directly and most efficiently absorbed by said boiler. I provide 110 a burner member which is highly refractory and capable of being rendered highly incandescent by the combustion of the fuel on its upper side, and I introduce the fuel on this upper side and in the zone where the 115 combustion takes place, the fuel being at the time of its introduction in a finely divided state, or in a vaporized condition, and properly mixed with air. In this construction the refractory member or hearth is given 120 the form of a substantially square bowl or dish-shaped member E which is open at its upper end and which embraces the lower open portion of the boiler casing or inclosure up to the partition wall which divides 125 the two boiler compartments, the upper edge of the burner member being fitted to the boiler to prevent any egress of the heat or entrance of air from the exterior. The burner member or hearth while being gen- 130

erally square to conform to the boiler, has its lower corners and angles rounded off or curved to form a generally rounded surface to direct the incoming fuel as will hereinafter appear. This bowl or dish is deep enough to form beneath the boiler a suitable combustion chamber in which the fuel whether it enters in an atomized or finely divided state or in the form of vapor, is intensely burned. In this particular structure the fuel is conducted into the central portion of the burner by means of a bell-shaped tube or delivery member 20 which is positioned above but in comparatively close relation to the central raised portion or hump 21 in the bottom of the refractory hearth, these parts being arranged so as to provide an annular slot or space 22 between the fuel pipe or member and the burner member, and being so formed and proportioned that the finely divided or vapor fuel mixture is directed in a comparatively thin sheet or film so to speak on the interior surface of the bottom wall portion of the refractory hearth where it burns intensely on or in contact with or in proximity to this surface. If by chance any of the fuel in unconsumed or partially unconsumed condition should reach the side walls of the burner the curvature of these walls deflects it back into the immediate combustion zone where the combustion is completed, but in any event the fuel burns intensely within the combustion chamber especially in proximity to the surface of the hearth or burner member.

The curvature of this surface creates a whirling motion of the fuel and products of combustion within the said chamber.

The refractory hearth or burner quickly becomes highly incandescent and by reason of its presence in the zone of or in proximity to the zone of combustion it acts catalytically to increase the completeness and intensity of combustion, and in order to utilize the catalytic agency or effect of the burner to the fullest extent I prefer that it, or at least its interior surface, be of a very porous or cellular nature whereby the effect of these pores or cells act to retard the movement of the fuel and retain it in the zone of combustion for a longer period of time. It will be understood that in the initial combustion or starting condition of the apparatus the parts are cold or comparatively so and the hearth or burner member has not of course become incandescent, hence with respect to the initial operation I provide preliminary heat for the purpose of initiating combustion of the incoming fuel. In the structure shown this initial or starting heat is produced by means of an electric spark or preferably a coil of suitable wire rendered incandescent by an electric current. The wire coil 23 is mounted on the

inner end of a removable plug 24, one terminal of which is grounded on the mechanism and the other terminal at the outer end is connected to a suitable source of current 25 by means of the conductor 25^a, this circuit being automatically controlled as will later appear. The starting coil is positioned just within the bell mouth of the delivery tube in the zone of the incoming fuel where the fuel will be started or preliminarily ignited. Having thus initiated combustion, which of course is practically instantaneous, the fuel will continue to burn on the inner surface of the hearth and in the combustion chamber and the refractory catalytic hearth gradually become incandescent and further builds up and sustains the process of combustion in its maximum. This building up process however is very rapid and is in practice actually a matter of only a few seconds. And this is true whether the fuel comes to the starter and burner in simply a finely divided atomized state or in a vaporized condition. However, in the arrangement shown I introduce the fuel into the delivery tube in a finely pulverized or atomized state but mixed or intermingled with the proper proportion of air to promote and sustain combustion. And when starting the process of combustion, the mixture reaches the igniter or hot wire in this condition. As the intensity of combustion increases in the burner, however, the delivery tube becomes heated to an extent to convert or at least partially convert the atomized fuel into vapor which being properly mixed with air, enters the combustion zone in a condition to immediately enter into the process of combustion. For convenience of construction and accessibility I removably mount the igniter plug in a ring 27 of metal which is fitted within a suitable opening in the humped central portion of the refractory burner member. This ring is cast or formed integral with the delivery tube, being connected thereto by several small web portions 28 which do not interfere with the space for the passage of the fuel into the combustion chamber.

An air blower H is connected to the delivery tube 20 which, as shown in the drawings, is turned horizontally and brought out at one side of the burner member just beneath the boiler. The outlet end 30 of this blower connects directly with the outer end 120 of the fuel delivery tube. The horizontal portion 31 of the delivery tube, however, is contracted or reduced in diameter at a point just inside the burner wall thus forming a venturi to increase the velocity of the air. At this contracted portion a fuel nozzle 32 is positioned whereby the structure forms an atomizer or pulverizer to finely divide the fuel and at the same time mix or intermingle it with a proper proportion of air.

The liquid fuel nozzle extends through the fan or blower casing and connects with a suitable source of liquid fuel supply, a valve 33 being provided to regulate the flow of oil. The air intake pipe 34 of the blower extends up and connects with a funnel or casing 35 which incloses a portion of the condenser cells as hereinbefore intimated. As a result the air taken in by the blower circulates around the condenser cells and absorbs the heat from the exhaust steam.

Now in order to govern the production or generation of steam in accordance with the varying demands upon a plant of this character, and to maintain the pressure substantially uniform, I provide automatic regulating mechanism which is arranged to be responsive to the pressure of the steam. On the side of the boiler or in any other suitable place I provide a cylinder 36 having a piston 36^a movable therein responsive to the steam pressure of the boiler. This cylinder is connected to a pipe line 40' leading from the lower or water manifold 14 of the boiler so as to get the correct boiler pressure without being subject to the varying steam temperatures. Opposing the movement of the piston is a coiled spring 37 in the cylinder. The movement of the piston in response to the water pressure is arranged to automatically govern the operation of the burner. In this structure the intake pipe of the blower has a butterfly valve 39 which governs the quantity of air passing to the blower. The valve has an operating lever 40 which is connected by a pin and slot connection 41 to an arm 42 on the piston rod 43. As the pressure of steam increases in the boiler the pressure of the water, of course, correspondingly increases and the regulator operates to reduce the quantity of air through the intake pipe. This restricts the combustion in the burner and reduces its temperature thereby reducing the generation of steam. Should this action continue until the air is practically cut off the mechanism will then operate to stop the blower. In this structure the blower is intended to be driven by a small electric motor connected in the circuit 44 from the source of current 25, and this circuit as well as the igniter plug circuit is controlled by a pair of contacts 46 and 47, these contacts being in the conductor 48 which is common to both the motor and plug circuits. The one contact 47 is stationary and is grounded on the mechanism. The other contact 46 is a pivoted arm which has an end portion 49 positioned in the path of movement of the end of the piston rod 43 at the lower end of the range of movement thereof, this pivot corresponding to a position of the butterfly valve where the air supply is so far cut off as to make an insufficient mixture. Thus when the mixture

reaches this point the regulator automatically stops the blower and simultaneously opens the igniter plug circuit, the result being that the supply of fuel to the burner is cut off and combustion ceases. When the boiler pressure is relieved, however, the piston moves upward in the cylinder and permits the contacts to make connection, starting the blower and igniter plug and the combustion of the fuel recommences, the igniter plug being again in operative condition to re-ignite the fuel in the event that the refractory burner cooled down too much during the period of rest. Thus, the operation of the boiler and burner is mutual and automatic and very accurately responsive to variable and sudden demands on the mechanism. I also provide a suitable hand switch 50 positioned conveniently for the operator and by means of which he is given control of the mechanism. By closing the switch he starts the motor and the igniter plug and from then on the regulation and control is automatic.

I claim:

1. In combination, a heat inclosure shell, a refractory fire-pot forming a bottom closure for said shell, a liquid-fuel atomizer for projecting a combustible mixture of finely divided fuel and air downward against the bottom of said fire-pot, and an electrical ignition device arranged to initiate combustion of said mixture.

2. In combination, a fire-pot, a refractory shell completely covering said fire-pot, a fuel atomizer for projecting a finely divided fuel and air into said fire-pot, an electrical igniter for igniting the mixture, and a regulator for automatically controlling the temperature within said shell.

3. In combination, a fire-pot forming a combustion chamber open at its top, a fuel atomizer for projecting finely divided fuel mixture downward against the bottom of said fire-pot, an electric ignition device for igniting said fuel mixture, an inclosure embracing the open top of said fire-pot and in which the hot gases of combustion rise directly upwardly therein.

4. The combination of a refractory bowl-shaped, imperforate fire-pot open at its top, a tubular member projecting into said fire-pot, a liquid fuel nozzle positioned in said tubular member, a blower connected to said tubular member to finely divide the liquid fuel and project it into said fire-pot, and a refractory lined shell inclosing the top of said fire-pot having an outlet at its upper end for the products of combustion.

5. The combination of a refractory bowl-shaped, imperforate fire-pot open at its top, a tubular member projecting into said fire-pot, a liquid fuel nozzle positioned in said tubular member, a blower connected to said tubular member to finely divide the liquid

fuel and project it into said fire-pot, an electric ignition device for initiating combustion of said fuel positioned beneath the inner end of said tubular member, and a refractory 5 lined shell inclosing the top of said fire-pot having an outlet at its upper end for the products of combustion.

Signed by me at Chicago, Ills., this 5th day of Sept., 1916.

ABNER DOBLE.
